Primary Examiner—Stacia Cadmus

(74) Attorney, Agent, or Firm—Jon Carl Geallow

(57) CLAIM

The ornamental design for a truck tent, as shown and described.

DESCRIPTION

FIG. 1 is a perspective view of a truck tent illustrating the present design;

FIG. 2 is a front elevation view thereof.

FIG. 3 is a top plan view thereof.

FIG. 4 is a rear elevation view thereof; and,

FIG. 5 is a side elevation view thereof.

The broken line showing of environment is for illustrative purposes only and forms no part of the claimed design.
